BUCKLE.

1,405,471.

Specification of Letters Patent. Patented Feb. 7, 1922.

Application filed May 21, 1920. Serial No. 383,114.

To all whom it may concern:

Be it known that we, WILLIAM WIENER and MERVIN G. WIENER, citizens of the United States, and residents of Newark, in the county of Essex and State of New Jersey, have invented new and useful Improvements in Buckles, of which the following is a specification.

This invention relates in general to 10 buckles and more particularly to a friction buckle whereby the belt, strap or the like is held in adjusted position by frictional engagement rather than by penetration of any portion of the buckle through the belt 15 or strap.

The objects of the invention are to provide a buckle of the character described embodying novel features of construction whereby a maximum amount of frictional 20 engagement is obtained between the buckle and belt or strap; to secure with slots in substantially the same plane such a tendency of the belt to twist as gives increased holding friction; to secure said 25 tendency of the belt to twist or bend transversely of its length both out of its plane and in its plane; to secure double tendencies to so twist, to provide a buckle having slots therein arranged diagonally or obliquely of the belt as it passes through the 30 buckle; to thus ensure that as the belt threaded through said slots is brought under tension it is crimped along transverse lines extending obliquely or diagonally of its 35 length, whereby the twisting action above-described is secured; to obtain a one-piece buckle having a plurality of slots to provide a belt end attaching bar, some of the edges of which slots are disposed diagonally or obliquely of the belt, and to obtain other 40 results and advantages as may be brought out by the following description.

Referring to the accompanying drawing, in which like numerals of reference indicate 45 the same parts throughout the several views.

Figure 1 is a plan view of a buckle embodying our invention;

Figure 2 is a similar view showing a belt or strap attached to and threaded through 50 the buckle;

Figure 3 is a vertical longitudinal sectional view taken on the line 3—3 of Fig. 2;

Figure 4 is a plan view of a modified 55 form of buckle embodying our invention, and

Figure 5 is a sectional view taken on the

line 5—5 of Fig. 4, showing a belt attached to and threaded through the buckle.

In the specific embodiment of the invention illustrated by Figures 1 to 3, inclusive, 60 of the drawings, the buckle is shown formed of a single piece of suitable material 1, such as metal, horn or the like, said piece of material being provided with a transverse slot 2 therein which is arranged at substantially 65 right angles to the longitudinal edges of the buckle and substantially midway of its length. Adjacent one end of the buckle 1 is formed a triangular shaped slot 3, the inner edge 4 of which is substantially 70 parallel to the slot 2 while the outer edge 5 thereof is disposed at an angle to said edge 4 so as to extend diagonally or obliquely of the length of the buckle 1. A third slot 7 is arranged adjacent the opposite end of the 75 buckle, upon the side of the slot 2 opposite the slot 3, said slot 7 being disposed at an angle to the slot 3 and extending diagonally of the buckle in a reverse or diverging relation to said slot 3. Preferably the slot 7 80 is inclined to the middle slot 2 at substantially the same angle as the outer edge 5 of the slot 3, as shown.

A belt or strap end attaching bar 8 is formed between the slots 2 and 3 to which 85 one end 9 of a belt or strap 10 is preferably attached, the belt end 9 being passed forwardly through the slot 3 from the back of the buckle over the bar 8 and returned through the slot 2 to lie flat upon the body 90 of the belt as shown by Figure 3, and be secured thereto by sewing or any other suitable or well known means. The free end 11 of the belt after passing around the person or object to which it is to be applied is 95 threaded from the back of the buckle forwardly through the slot 7, over the front of the buckle and attached end 9, and then backward through the slot 3 to project from under the buckle at the end thereof. 100

When the belt thus threaded through the slots, as shown in Figures 2 and 3, is placed under tension which would tend to draw the free end 11 thereof from the slots 7 and 3, the belt tends to straighten and flatten in 105 its plane and each oblique or diagonal biting edge tends to bend the belt transversely out of its plane; the effect of this is to cause the front surface of the belt to more firmly engage the edge of the slot away 110 from the middle transverse line of the buckle, at the end of the slot nearest said middle

transverse line, and the rear surface of the belt to more firmly engage the other edge of the slot at its opposite end or end farthest from the middle transverse line of the buckle. 5 By having two diagonal slots, the effect is increased or doubled, and furthermore the effect of an oblique or diagonal slot is to give the belt a tendency to bend transversely in its own plane, which under lengthwise 10 strain upon the belt in normal use results in increased friction or bite of the buckle upon the belt and thus increased holding power. Thus the effect of the oblique or diagonal arrangement of the slots, when the belt is 15 placed under tension tending to straighten and flatten it in its plane, is the production of additional friction between the under-surfaces of the opposite ends of the buckle and the belt and between the ends of the belt, and thus increased holding power, over 20 that which would be obtained by transverse slots at right angles to the belt.

It should also be noted that longer slots are obtained by arranging them diagonally, 25 than if they were at right angles to the length of the belt, and that greater friction surface, resulting in further increased biting friction, is secured in this way.

In the modified form of our invention 30 illustrated by Figures 4 and 5 of the drawings, the buckle 12 is provided with a central transverse slot 13 similar to the slot 2 above described, and a triangular slot 14 adjacent one end of the buckle similar to 35 the slot 3, said slot having its outer edge 15 arranged diagonally of the buckle. Adjacent the other end of the buckle a third slot 16 is formed, said slot being arranged substantially parallel to the diagonal edge 15 of 40 the slot 14 so as to extend diagonally of the buckle 12.

One end 17 of the belt 18 is fixed to the bar 19 between the slots 13 and 14 in a manner similar to that described in connection 45 with Figures 1, 2 and 3, and the free end 20 of the belt is threaded from the rear of the buckle forwardly through the slot 16 over the front of the buckle and the fixed end 17 and returned through the slot 14. It will 50 thus be seen that the construction and operation of this form of our buckle is substantially the same as that of the buckle shown in Figures 1 to 3, except that the diagonal edges of the slots 14 and 16 are parallel instead of divergent. The difference in the 55 results of this modified construction is that the tendencies to edgewise bending in the plane of the belt, imparted by the two parallel slots, are in opposite directions or toward 60 opposite edges of the belt, whereas the corresponding bending tendencies of the diverging slots first described are in the same direction or toward the same edge of the belt. The results of the two constructions 65 are believed to be the same in all other re-

spects, but the two forms are shown to illustrate that our invention may be embodied in many various forms, so long as diagonal biting edges are present.

Obviously buckles constructed in accordance with our invention can be used for many different purposes and with various kinds of belts or straps of any material, for instance, with waist-line garment supporting belts, limb encircling garment supporters, bale-ties, driving belts, etc.; while the examples just given are all forms in which the belt or strap encircles something, we desire it clearly understood that our invention is just as applicable to use for connecting the meeting ends of straps which are attached at their other ends to separated points or objects, such for example as are found in many parts of harness for horses, in the retaining cross straps of a suit case, etc. In 85 fact, our invention can be used for any purpose to which it can be adapted, and by the term "buckle" as used we mean any member made in accordance with or embodying our invention; the slots may be open at one end 90 or closed as shown, and the detail construction can be varied in many other ways without departing from the spirit or scope of the invention. We do not desire to limit ourselves at all except as required by the following claims when construed in the light of the prior art.

Having thus described the invention, what we claim is:

1. The combination of a buckle having a 100 body portion with spaced slots transverse to the length of the buckle, said slots having their edges farthest apart forming biting edges oblique to the length of the buckle, and a strap arranged in alignment with the 105 length of the buckle and having a free end portion adapted to lie at one side of the buckle body portion between said slots and passing to the other side of said body portion through said slots to extend in opposite 110 directions in substantially the plane of the buckle lengthwise of the same and beyond it at both of its opposite ends.

2. The combination of a buckle having a 115 body portion with spaced slots transverse to the length of the buckle, said slots having their edges farthest apart forming biting edges oppositely oblique to the length of the buckle, and a strap arranged in alignment with the length of the buckle and having a 120 free end portion adapted to lie at one side of the buckle body portion between said slots and passing to the other side of said body portion through said slots to extend in opposite directions in substantially the plane 125 of the buckle lengthwise of the same and beyond it at both of its opposite ends.

3. The combination of a buckle having a 130 body portion with spaced slots transverse to the length of the buckle, said slots having

- their edges farthest apart forming biting edges oblique to the length of the buckle and said body portion having intermediate said slots strap-secur ing means, and a strap 5 having one end held by said securing means with the strap in alinement with the length of the buckle and having its other end portion adapted to lie at one side of the buckle body portion between said slots and passing 10 to the other side of said body portion through said slots to extend in opposite directions in substantially the plane of the buckle lengthwise of the same and beyond it at both of its opposite ends.
- 15 4. A buckle having a body portion with spaced slots transverse to the length of the buckle and adapted to receive a strap lying at one side of said body portion between said slots and passing to the other side of the 20 body portion through said slots to extend in
- opposite directions in approximately the plane of the buckle, said slots having their edges farthest apart oblique to the length of the buckle and said body portion having intermediate said slots a third slot transverse 25 to the length of the buckle forming with one of the other said slots means for securing an extremity of the strap in alinement with the buckle.
5. A buckle with a body portion having a middle slot therein substantially at right angles to the longitudinal edges thereof, a triangular slot at one side of said middle slot having its edge next to the middle slot substantially parallel thereto, and a third 30 slot at the opposite side of said slot from said triangular slot angularly disposed with respect to said middle slot.
